PROCESS FOR RECOVERY OF HYDRO-CARBON OIL FROM SHALE

William L. Thompson, Elizabeth, N. J., assignor
to Standard Oil Development Company, a corporation of Delaware

Application August 10, 1944, Serial No. 548,884

2 Claims. (Cl. 202—14)

1

The object of the present invention is to provide a process and suitable apparatus therefor for recovering hydrocarbon oil from tar sands and/or shale.

Prior to my invention others had proposed methods for recovering hydrocarbon oils from tar sands and shales. Usually the prior methods involved heating of the oil-containing material to convert the hydrocarbon oil-forming material into volatile constituents and a fixed carbon. These operations were performed in a retort in which the shale or tar sand was treated in a process essentially intermittent.

According to my present invention, I provide a process and suitable apparatus therefor whereby tar sands and/or shales from which hydrocarbon oils are to be recovered, are heated in powdered form, or at least in divided form, to a temperature sufficiently high to cause coking of the hydrocarbon oil-forming constituents with the result that the hydrocarbon oil is converted to a volatile product and a tar or coke. The volatile hydrocarbons are then treated according to the customary oil refinery practice and separated into various fractions, such as normally gaseous hydrocarbons, gasoline constituents, gas oil, tar, coke, and the like, as desired. The fixed carbon or coke which is left on the sand or spent shale is burnt to supply heat for the process.

The present application describes in detail an arrangement of apparatus elements for using the heating value of the coke to carry out the coking reaction. In general, the method comprises an application of the so-called "fluid-solids" technique to this problem. By "fluid-solids" technique, I mean an operation in which the solid material undergoing treatment is maintained in a dense suspension in a delayed settling zone by controlling the velocity of a gasiform material flowing therethrough at a sufficiently low value that the solid material forms a dense, turbulent, mobile mass of solid in gas resembling a boiling liquid, all of which will more fully and at large appear hereinafter.

In the accompanying drawing, I have shown diagrammatically a suitable apparatus in which a preferred modification of my invention may be carried into practical effect.

Referring in detail to the drawing, a tar sand or a shale, the latter in subdivided form having a particle size of, say, 100 mesh up to $\frac{1}{4}$ inch in diameter, is introduced into the present system by a conveyor 1 and thence discharged into a feed hopper 2 from which it is withdrawn into a screw

2

conveyor 3, which may be of the compression screw type. The feeder charges the sand or tar in a line 4 where it mixes with hot, burnt and spent shale or tar sand from line 5 and subsequently with a liquid product of the coking which is charged into line 4 from line 6, the source of this liquid material in line 6 being more fully identified hereinafter. At this point I will simply point out that it is a hydrocarbon in liquid form produced as a result of coking. The mixture of spent shale or tar sand and hydrocarbon, the latter being essentially vaporized by the hot spent shale or tar sand, forms a suspension in line 4, which suspension is carried into the bottom of coking drum 10 which, as can be seen, is essentially a cylindrical shell or case having conical upper and lower sections. In the coking zone 10 the linear velocity of the gasiform material is controlled within the limits of from $\frac{1}{2}$ to 10 ft. per second, depending upon the particle size of the solids therein contained. If, for instance, the solids have a particle size of around 200 mesh, the gas velocity in the vessel 10 is from $\frac{1}{2}$ to 3 ft. per second, which will cause the formation of the dense, turbulent, fluidized mass which I have previously referred to. Actually another way of describing the reaction vessel 10 is to say that it is a "delayed settler" wherein the velocity of the gas is insufficient to carry the main bulk of the product overhead and out of the reactor but sufficient, nevertheless, to support a body of the solid in the reaction zone to form the dense phase suspension. Of course, if the particle size is $\frac{1}{4}$ inch or larger on the average in diameter, the gas velocity must be somewhat higher, say up to 10 to 12 ft. per second. In the case where the shale or tar sand is in the form of relatively large aggregates, the heat with which it is confronted in the reaction zone serves to decompose the agglutinants contained in the lumps of shale, and the like, and to cause the shale and the like to disintegrate physically.

A temperature of 900° F. to 1000° F., approximately, is maintained within the reaction zone 10. The pressure is not critical and may be atmospheric or a few pounds above atmospheric, in other words, sufficient to overcome pressure drops in the system. The shale or sand remains resident in the reaction zone for a sufficient period of time to effect the desired conversion. In the case of tar sand, this residence time is from 1 to 3 minutes. The result of the coking or heating operation in the vessel 10 is to convert high molecular weight constituents of the shale or sand into volatile hydrocarbons which are with-

drawn through line 12 and into a spent material which is withdrawn through a draw-off pipe 90.

Referring again to the interior of the reaction zone 10, I provide a foraminous member G, which may be a screen or grid, to aid in the distribution of the gasiform material in the reaction zone, and under the flow conditions which I have named there will be an upper dense phase level, which I have indicated at L which is fixed by fixing the amount of powdered shale or sand which is maintained in the reaction zone and by the velocity of the gas. Essentially, when the velocity of the gas is sufficiently low to maintain the dense phase suspension previously referred to, the height of the level L is controlled by the rate at which solid material is withdrawn. A controlled amount of material is withdrawn through 14 and is discharged into a pipe 16 where it mixes with air or other oxygen-containing gas, as will subsequently appear. It should be pointed out, however, that in order to cause good flowability in line 14, the same should be provided with a number of taps (not shown) into which a slow current of gasiform material, such as flue gas, steam, normally gaseous hydrocarbons, and the like, are forced to prevent bridging and/or plugging of draw-off pipe 14. The shale or tar sand, as stated, is discharged into air stream 16 where it forms a suspension which is then conveyed into the bottom of a combustion zone 20. This combustion zone is similar in shape and construction to coking zone 10, that is to say, it consists of a cylindrical case or shell having conical upper and lower sections and is also provided with a distribution screen or grid G. Here also the velocity of the air and the amount of shale maintained in the combustion zone 20 is adjusted so as to form a dense phase upper suspension at L, in which suspension the fixed carbon on the sand or shale is consumed by combustion thus causing heating of the spent shale to a temperature of 1000° F. to 1175° F., whereupon the spent shale is withdrawn through pipe 5 and mixed with the fresh shale or tar sand and recycled to coking drum 10, the hot shale providing the heat necessary to support the pyrolytic action taking place in coking or distilling vessel 10.

The amount of spent shale circulated to the combustion zone by line 16 and admixed with the cold fresh shale or tar sand in line 4 should be sufficient to raise the temperature of the mixture to the reactor temperature and to supply heat for the cracking reaction. This would require in the order of from 5 to 10 parts by weight of hot spent shale or tar sand per part of cold fresh shale or sand. It is also pointed out that draw-off pipe 5 is provided with a flow control valve 7 which controls, of course, the amount of spent shale withdrawn through line 5 and is also provided with a plurality of taps into which a gas, such as air or flue gas, may be continuously fed to prevent bridging or plugging of draw-off pipe 5.

Referring back again to distillation and/or coking zone 10, the gasiform material above the level L becomes or is greatly depleted in solid content since the main body of the solids remains in the suspension below L. Thus by controlling the amount of solid and the velocity in 10, as previously indicated, the upper dense phase level will be at L and will have a weight of 15-25 lbs. per cubic foot. Above L the concentration of solid in the gas may be lowered to the extent that it weighs only about 0.025 to 0.030 lb. per

cubic foot. This dilute suspension passes through a number of cyclones which I have indicated at C disposed in the upper conical section of 10, which cyclones cause the separation of the solid from the gas by centrifugal action and the return by gravity of the separated solid to the main body between G and L, while the gasiform material is withdrawn overhead through line 38 containing only minor amounts of entrained solid. It is at a temperature of around 900° F., to 975° F. and it passes into a "knockdown" drum or cooler 31 where it is partially cooled, say to a temperature of 650° F. for the purpose of condensing out the heavier oils, which oils will contain the unseparated fines. This slurry is withdrawn from the bottom and thence is forced by pump 33 into line 6 for recycling to 10, as previously indicated.

Overhead from "knockdown" drum 31, I withdraw through line 35 a hydrocarbon fraction in gasiform state which is then discharged into a heat exchanger 40 in which further cooling and condensation takes place. The product from this exchanger, which is part liquid and part vapor, is withdrawn through line 42 and discharged into a water quench zone 45 from which I withdraw normally gaseous hydrocarbons overhead through line 46, while the quenched material is withdrawn through line 47. The quenching water is introduced through line 50. The quenched material is then pumped by pump 48 into a separator 51 from which the hydrocarbon oil may be withdrawn through line 52 while the water is withdrawn through line 53.

Referring to the material in line 6, a portion thereof may be bypassed through line 61 into a heat exchanger 62 in which it is cooled to a temperature of 300° F. to 500° F. and thence discharged via line 63 into "knockdown" drum 31.

Heat exchangers 40 and 62 are cooled by means of water from drum 64 introduced through lines 65 and 66, respectively. Steam generated in heat exchangers 40 and 62 at about 125 lbs. per square inch is returned to drum 64 through lines 67 and 68, respectively, and withdrawn from the drum through line 69.

Referring again to combustion zone 20, above L there is a second dense phase suspension which I have designated as S₂. This is formed by interposing a second foraminous member G₂ at a point spaced above L and here also by controlling velocity and the amount of solid there is a second dense phase suspension and an upper level at L₂. In other words, in combustion zone 20 I have two separated dense phase suspensions. Interposed, as will be noted, in the second and/or upper dense phase suspension is a coil 70 containing water, which water is converted into steam by heat interchange with the hot spent shale, which steam is discharged into vessel 72 and withdrawn through line 73, the water being fed to the coil through line 74. Thus I have provided means for forming a quantity of steam which may be used in my present process. Above L₂ the concentration

of solid in the gas, which in this case is regeneration vapors, is greatly depleted so that whereas the suspension weighs from 15-25 lbs. per cubic foot in both dense phase suspensions, in the space above L₂ it may be of the order of a density of 0.025 to 0.030 lb. per cubic foot, and this dilute suspension is then forced through one or more centrifugal separators C disposed in the upper portion of 22 where the suspension in passing through is separated from entrained solids which are returned to the upper dense phase sus-

pension, while the regeneration fumes are withdrawn through line 80, thence passed through a gas turbine 81 before they are vented from the system through line 82 thus providing a portion of the power required to operate air compressor 84 which pumps air to the preheating zone 92 through line 94, as described above, and to combustion zone 20, and to storage zone 152, described below. The turbine 81 may be operated on the same shaft as steam turbine 83 which operates compressor 84.

Referring again to distillation and/or coking zone 10, the spent shale to be rejected from the system is withdrawn through a line 90 and discharged into a preheater 92 where it contacts in the form of a dense suspension, the air entering said preheater through line 94. The air contacts the hot shale and is preheated thereby and is withdrawn through line 100, and it is this preheated air which eventually mixes with the spent shale withdrawn from distillation zone 10 through line 14 to form the suspension which is conducted to combustion zone 20, as previously described.

In preheating zone 92, the velocity of the air is fixed within the limits of from $\frac{1}{2}$ to 10 ft. per second, preferably $1\frac{1}{2}$ to 3 ft. per second, so as to form the dense phase suspension having an upper level at L. Here also I provide a screen G which serves to aid in the distribution of the air. In order to provide a further quantity of steam for use in the process or for some other useful purpose, I may interpose a water coil 115 in the mass of dense suspension, in which water is preheated or converted to steam. The spent shale is withdrawn from preheater 92 through line 130, mixed with air from line 131 and conducted into the top of a storage vessel 152, thence withdrawn through line 160 and discharged into a car or other conveyance 162 and withdrawn from the system. Here also, in order to recover heat for some useful purpose, I dispose within the storage zone 152 a water coil 170 in which boiler feed water may be preheated.

Thus I have described an operation for converting shale or tar sands into hydrocarbon oils which may be subsequently processed to produce gasline, gas oil, heating oil, and the like.

My present invention involves essentially the following novel features:

1. Utilization of the fluid-solid technique to treat the raw material continuously and efficiently in an economical manner.

2. To make the system substantially self-supporting regarding heat requirements by burning the fixed carbon on the spent shale or tar sands.

3. Economizing in utilities by utilizing the energy of regeneration fumes and hot spent shale for operating waste heat boilers and turbines.

My process is suited for recovering valuable hydrocarbon oils from natural deposits known as Athabaska sands, oil shales, and the like.

Many modifications of my invention will be

apparent to those skilled in the art without departing from the spirit thereof.

What I claim is:

1. In the continuous process of recovering hydrocarbon oil from oil-bearing minerals by distilling said minerals in a fluidized bed of solids maintained in a distillation zone, withdrawing spent solid residue, burning withdrawn residue with a combustion-supporting gas in a fluidized bed maintained in a combustion zone, and returning heated residue from said combustion zone to said distillation zone to supply heat to the latter, the improvement which comprises preheating said combustion-supporting gas in direct contact with hot fluidized solid distillation residue withdrawn from said distillation zone, carrying out said burning in two separate superimposed fluid beds within said combustion zone, vaporizing a liquid by heat exchange with the upper one of said superimposed beds, transferring substantially all the heat generated in the lower one of said superimposed beds to the materials forming said lower superimposed bed, withdrawing all of said returning heated residue from said lower superimposed bed, cooling the volatile effluent of said distillation zone just sufficiently to condense a heavy oil fraction, mixing said returning heated residue with said minerals and said condensed oil fraction outside said zones to vaporize said oil fraction and to form a dilute solids-in-gas suspension, and passing the suspension so formed to said distillation zone.
2. The method of claim 1 in which hot fumes are withdrawn from the combustion zone and passed through a system adapted to recover at least a portion of their energy content as kinetic energy.

WILLIAM I. THOMPSON.
